UNITED STATES PATENT OFFICE

2,656,273

PHOTOGRAPHIC DEVELOPERS CONTAINING DIAMINO-PROPANOL TETRACETIC ACID.

Richard W. Henn and Douglas E. Piper, Rochester, N. Y., assignors to Eastman Kodak Company, Rochester, N. Y., a corporation of New Jersey

No Drawing. Application February 12, 1952,
Serial No. 271,284

4 Claims. (CL. 95—88)

1

This invention relates to developers containing therein diaminopropanol tetracetic acid as an agent of addition thereto.

In the developing of photographic emulsions, calcium may enter the developer solution either from the water supply or from the photographic emulsion itself, particularly if gelatin is employed as the carrier for the silver halide. This calcium may precipitate as the carbonate, sulfite, or borate to form sludge in the solution; scale on the equipment, and scum on the photographic materials, and hence may have an adverse effect on the quality of photographic films processed therewith. The prevention of these precipitates has previously received some attention, and this difficulty of the presence of calcium in developer solutions has been overcome to some extent by the use of compounds which hold the calcium in the form of un-ionized complexes. Compounds which are especially characterized by this property, such as alkali hexametaphosphates and alkali tetraphosphates, have been used in developing solutions to reduce the formation of the calcium sulfite scum on the films, and precipitation of calcium in the developer. However, when these phosphates stand in aqueous solution, they gradually hydrolyze to the orthophosphates, which not only possess no properties inhibiting calcium precipitation, but may precipitate the calcium in the form of calcium phosphate. Also, if orthophosphate is carried over to the alum fixing bath, there is the possibility of the precipitation of aluminum phosphate thereby.

Some oxygen acids, such as citric, tartaric, gluconic, etc., have proved useful as calcium sequestering agents in photographic developing solutions, but usually these acids are so weak that, in most instances, it is desirable to supplement their effect by also adding polyphosphates. Also, the use of amino polyacetic acids, such as ethylenediamine tetracetic acid and nitrotriacetic acid in developing solutions, has previously been disclosed, but these compounds, although stable and effective, possess the undesirable property of catalyzing oxidation of the developer by the air in the presence of traces of iron in the developer solution. For example, a developer containing 0.5% of one of these materials, together with 8 p. p. m. of iron and 2 p. p. m. of copper, will cause very rapid oxidation of the developer when air is bubbled through the solution for 2 hours.

One object of our invention is to provide a developer composition which contains a calcium sequestering agent having good stability, high sequestering potency and is innocent of the promotion of developer oxidation, even though traces of iron and other metals may be present. Another object of our invention is to produce photographic developers having improved properties. A further object of our invention is to prevent

2

the formation of calcium-containing sludges, scums, and scales in the developer solution. A still further object of our invention is to inhibit any local desensitization of the emulsion when immersed in the developer solution. Other objects of our invention will appear herein.

We have found that the objects of our invention may be accomplished by the addition of 1,3-diamino-2-propanol tetracetic acid to a developer composition in an amount constituting at least $\frac{1}{2}\%$ of the solids in the composition. The diaminopropanol tetracetic acid may be added either to the developer composition in dry form or it may be incorporated in the aqueous solution of the developer, preferably prior to contacting the photographic materials with the developer solutions. We have found that the presence of the diaminopropanol tetracetic acid in the developer solution not only prevents the formation of any calcium precipitate therein, but in addition, in the case of certain photographic papers, a type of local desensitization thereof, known as "freaking," is prevented. Freaking involves the failure of an exposed emulsion to develop at the edges of areas which have been spotted with developer prior to complete wetting of the emulsion layer, as, for example, by splashing. This phenomenon is avoided completely when diaminopropanol tetracetic acid is present, particularly in concentrations of at least 6 to 10 grams thereof per liter of the developer.

The diaminopropanol tetracetic acid may be added to any of the commonly employed developers, either those types which contain borate salts, as the alkaline material, or those which contain a carbonate, as the alkaline material. Typical developers in which diaminopropanol tetracetic acid can be incorporated are the following:

I

	Grams
Monomethyl-p-aminophenol sulfate	2½
Hydroquinone	2½
Sodium sulfite, desiccated	30
Sodium metaborate (octahydrate)	10
Potassium bromide	½
Water to bring to 1 liter.	

II

	Grams
Monomethyl-p-aminophenol sulfate	3.1
Hydroquinone	12
Sodium sulfite, desiccated	45
Sodium carbonate, desiccated	67.5
Potassium bromide	1.9
Water to bring to 1 liter.	

In the above compositions, the diaminopropanol tetracetic acid may be employed in an amount of at least $\frac{1}{2}\%$ of the total solid content, and preferably in a proportion of 2 to 10% therein. It is apparent that the amount of calcium se-

questering agent which is needed will depend to a large extent upon the amount of calcium which will be present in the developing solution. This being the case, the proportion of diaminopropanol tetracetic acid which is employed will be within the judgment of the individual operator. The following example, however, illustrates a satisfactory relationship between the proportion of the diaminopropanol tetracetic acid and the calcium which is present.

Example 1

A developer containing monomethyl-p-aminophenol sulfate and hydroquinone developing agents and which was 0.5 molar with respect to sodium sulfite, and 0.07 molar with respect to sodium metaborate, and possessed a pH of about 9.8, was found to precipitate densely with the addition of only 0.25 grams of calcium chloride per liter. However, it was found that when the following quantities of diaminopropanol tetracetic acid were added per liter, the amounts of calcium chloride designated could be added without any precipitation:

Grams of Diaminopropanol-tetracetic Acid per Liter	Grams of Calcium Chloride per Liter
8	1.4
4	0.7
2	0.45

Example 2

Similar amounts of diaminopropanol tetracetic acid were added to the following developer, and similar amounts of calcium chloride per liter were added. It was found that no precipitation of calcium occurred.

	Grams
Monomethyl-p-aminophenol sulfate	3.1
Hydroquinone	12
Sodium sulfite, desiccated	45
Sodium carbonate, desiccated	67.5
Potassium bromide	1.9
Water to make 1 liter.	

Example 3

To illustrate the advantage of diaminopropanol tetracetic acid as regards promotion of oxidation of developer, 3 variations were employed as follows:

1. The developer formula of Example 1 with no sequestering agent added.
  2. Diaminopropanol tetracetic acid was added.
  3. Ethylene diamine tetracetic acid was added.
- Also incorporated in each were 10 p. p. m. of iron.

The three solutions were allowed to stand exposed to the air for 48 hours. Solutions 1 and 2 were found to remain relatively colorless and photographically active, while solution 3 was found to have oxidized to a deep brown color and was photographically inert.

Example 4

Two grams per liter of diaminopropanol tetracetic acid were added to a developer as specified in Example 1. Also to a developer replenisher having the following composition, N-methyl para amino phenol sulfate 5 grams, hydroquinone 10 grams, sodium sulfite 30 grams, sodium metaborate (octahydrate) 40 grams and water to make one liter, was added 8 grams of diaminopropanol tetracetic acid. An exhaustion test was carried

out on this developer using the equivalent of 600 eight by ten inch sheets of photographic film per gallon of starting developer. 1.8 gallons of the replenisher were used to maintain the volume constant during the test. No appreciable precipitation occurred, and after a little deposit containing gelatin, silver, etc., had been filtered off, the remaining solution stayed clear and free of further deposit through the incubation and storage tests lasting 30 days. The film which had been processed in the solution was found to be free of any deposit thereon. A control test using the same materials and carried out in like manner, but without the addition of the diaminopropanol tetracetic acid, yielded a copious precipitate of calcium compounds and, even after filtering the solution, a further deposit formed during the incubation and storage tests. Our invention is characterized by the sequestering of not only calcium, but magnesium or any other hard water cations which may be present in a developer solution. In using the diaminopropanol tetracetic acid in developer, it was found that the average sequestering value thereof was 550 millimoles of calcium per mole of the diaminopropanol tetracetic acid, and the action of this sequestering agent appeared to be substantially independent of the composition of the developer. Therefore, in order to obtain a complete sequestering effect, it is desirable to use the diaminopropanol tetracetic acid in an amount at least corresponding to this value.

Example 5

A further illustration of the advantages of the diaminopropanol tetracetic acid over other amino sequestering agents was obtained by adding 5 p. p. m. of iron to the developer of Example 2, dividing this, and modifying the separate portions by adding 4 grams per liter of (a) diaminopropanol tetracetic acid (DPT) or (b) ethylenediamine tetracetic acid (EDT) together with sufficient sodium hydroxide to neutralize the acid. Oxidation was produced by rapidly bubbling finely dispersed air through the solutions. The developer containing the EDT discolored rapidly, being quite brown in 1 hour and dark in 2 hours and without developing activity. The developer containing the DPT, on the other hand, discolored very little in 8 hours and lost no developing activity. Nitro triacetic acid and methylaminodiacetic acid have been found, like the ethylenediamine tetracetic acid, to also promote developer oxidation.

It is to be understood that, if desired, the incorporation of the diaminopropanol tetracetic acid in the developer may be accomplished by adding that material to emulsion compositions, and, as a result of treating those emulsions with developer solution, the diaminopropanol tetracetic acid will be thereby introduced into the photographic developer composition. Another means by which the diaminopropanol tetracetic acid may be incorporated in the developer is by incorporating it in coatings which may have been applied to the photographic film in its preparation. Upon processing, the diaminopropanol tetracetic acid will be extracted from this coating or coatings by the developer solution.

We claim:

1. A photographic developer composition comprising a silver halide developing agent and 1,3-diamino-2-propanol tetracetic acid.
2. An aqueous photographic developing solution comprising a solution of a silver halide developing agent and 1,3-diamino-2-propanol tetracetic acid in water.

3. A photographic developer in dry form comprising a silver halide developing agent and 1,3-diamino-2-propanol tetracetic acid.

4. A photographic developing solution comprising an aqueous solution of a silver halide developing agent and 6-10 grams per liter of solution of 1,3-diamino-2-propanol tetracetic acid.

RICHARD W. HENN.
